(57) **CLAIM**

The ornamental design for a blender, as shown and described.

DESCRIPTION

FIG. 1 is a perspective view of a blender showing our new design;

FIG. 2 is a front view of the blender of FIG. 1;

FIG. 3 is a left side elevation view of the blender of FIG. 2; FIG. 4 is a right side elevation view of the blender of FIG. 3;

FIG. 5 is a rear view of the blender of FIG. 2;

FIG. 6 is a top view of the blender of FIG. 1; and,

FIG. 7 is a bottom plan view of the blender of FIG. 1.

The broken lines showing a power supply cord, blender blade and bottom surface shown in FIGS. 1-7 are for illustrative purposes only and form no part of the claimed design.
